Primary Examiner — Mark A Goodwin

(57) **CLAIM**

The ornamental design for a road roller as shown and described.

DESCRIPTION

The patent or application file contains at least one drawing executed in color. Copies of this patent or patent application publication with color drawing(s) will be provided by the Office upon request and payment of the necessary fee.

1. Road roller

1.1 : Front

1.2 : Back

1.3 : Left

1.4 : Right

1.5 : Top

1.6 : Perspective

Fig.1 is a front view of road roller; Fig.2 is a back view thereof; Fig.3 is a left view thereof; Fig.4 is a right view thereof; Fig.5 is a top view thereof; Fig.6 is a perspective view thereof; bottom view is omitted because it is rare to be seen# the main design points of this design is shape; use of this design product is for compaction of road surfaces.

**1 Claim, 6 Drawing Sheets
(6 of 6 Drawing Sheet(s) Filed in Color)**
